UNITED STATES PATENT OFFICE.

CHARLES CAMERON BURNER, OF TRAVELLER'S REPOSE, WEST VIRGINIA.

GRINDING-MILL.

SPECIFICATION forming part of Letters Patent No. 299,340, dated May 27, 1884.

Application filed March 28, 1884. (No model.)

To all whom it may concern:

Be it known that I, CHARLES CAMERON BURNER, a citizen of the United States, residing at Traveller's Repose, in the county of Pocahontas and State of West Virginia, have invented certain new and useful Improvements in Grinding-Mills, of which the following is a description.

This invention relates to mills used for grinding apples into pomace preparatory to making cider thereof, and more particularly to that class of mills in which cogs slide out and in from a revolving wheel to crush the apples against a stationary opposite part.

The object of this invention is to provide means whereby the cogs may be slid out and in with mechanical certainty and ease, means whereby the apples may be gradually reduced to the fineness required, means whereby the cog-mortises may be kept clear, and means for cleaning the face of the revolving wheel.

To this end my invention consists in the construction and combination of parts hereinafter described and claimed, reference being had to the accompanying drawings, in which—

Figure 1 is a plan view of my mill, a portion being broken away. Fig. 2 is an end view of the same with the hopper removed and a portion broken away. Fig. 3 is a central longitudinal vertical section, part in elevation, and Fig. 4 is a detail in section.

A represents the stationary frame of the mill. B is a cylindrical hub fixed thereon, having one or more reverse spiral flanges, *a*, upon which the cogs C rise and fall as they are revolved with the wheel D, which is journaled to revolve upon the hub. These cogs stand in radial grooves in the wheel, and the wall of each groove on the front side of the cog is recessed at *b*, to form an escape for any pomace that may be crowded into the slot. This recess increases in size from the top downward and radially toward center, like a spout, in order that the pomace gathered therein may naturally work into the annular space *c* between the hub and the lower portion of the wheel, and drop thence into the trough E.

The machine is here shown as double, having two sets of fixed grinding-teeth, *d*, in the upper head, G. F is the hopper, having two inlets, *e*, one to each set of teeth. Each set of

teeth *d* is a series of inverted spiral steps, gradually decreasing in height from the first tooth, *d'*, to the last one, *d''*. The spiral flanges *a* are so circumferentially located relatively to each set of teeth that the cogs are raised thereby to their highest level just before they pass under the first tooth, *d'*, and then they begin to descend, gradually approaching nearer to the teeth until, as they pass under the last tooth, *d''*, they nearly touch it. By this means the cogs stand nearly as high as the apples when the latter are received, and the opposing teeth are at first so large as merely to split and break up the apples; but as the cogs advance, carrying the broken apples along, the parts of the latter are again and again divided by teeth standing nearer and nearer the plane of the wheel, until the pomace is at last forced out between the head G and the wheel D, which are nearly in contact with each other, thus being ground as fine as may be desired. The walls of the hopper-inlets *e* rest their lower edges on the upper face of the wheel, and the rear edge, *f*, of each inlet serves as a scraper to turn the pomace of the other mill off from the wheel into the trough E. The edges *f* may be provided with shoes of leather or iron to prevent wear.

J is an arm of the wheel D, upon which a lever, K, is secured by a clevis, L, to attach the team to for revolving the wheel. The upper portion of the wheel bears directly against the hub; but all that annular portion *c* below the flange is enlarged, in order that the wheel may be placed down over the flange in putting the machine together, and, further, to allow a space for the pomace which gathers in the recess to fall below.

What I claim as my invention, and desire to secure by Letters Patent, is—

1. The combination, with a stationary hub and grinding-surfaces projecting beyond the hub and supported thereon, of a wheel journaled to revolve on said hub, cogs loosely fitted in said wheel, and means, substantially as described, for raising and lowering the cogs, for the purpose specified.

2. The combination, with the stationary hub B and the spiral flanges *a*, fixed thereon, of the radially-slotted wheel D and the cogs C, fitted to slide in said slots, and notched to ride

upon the flanges *a*, as and for the purpose specified.

3. The combination, with the stationary hub *B*, the slotted wheel *D*, fitted to revolve thereon, 5 cogs *C*, loosely fitted in said slots, and means, substantially as described, for raising and lowering the cogs, of the radial teeth *d*, fixed upon the hub *B*, substantially as shown and described.

10 4. The combination, with a slotted wheel, cogs fitted therein, and means, substantially as described, for raising and lowering said cogs, of a series of teeth gradually decreasing in height, radially fixed relatively to the said 15 cogged wheel, as and for the purpose specified.

5. The combination, with the stationary hub *B*, the slotted wheel *D*, the cogs *C*, loosely fit-

ted therein, means for raising or falling said cogs, and means for opposing them with a stationary grinding device, of the hopper *F*, having two inlets, *e*, to the mill, said hopper resting on the wheel *D*, and provided with the scraping-edges *f*, as and for the purpose specified. 20

6. The combination, with the slotted wheel 25 *D*, of the cogs *C*, fitted therein, and means, substantially as described, for operating the same, the walls of said slots being recessed, as and for the purpose specified.

CHARLES CAMERON BURNER.
